UNITED STATES PATENT OFFICE.

ARNOLD PFAU, OF MILWAUKEE, WISCONSIN.

VENTILATOR.

1,389,896.

Specification of Letters Patent.

Patented Sept. 6, 1921.

Application filed June 12, 1916. Serial No. 103,062.

To all whom it may concern:

Be it known that ARNOLD PFAU, a citizen of the Republic of Switzerland, residing at Milwaukee, in the county of Milwaukee and 5 State of Wisconsin, has invented a certain new and useful Improvement in Ventilators, of which the following is a specification.

This invention relates to improvements in the construction and operation of ventilators or deodorizers for water closets and 10 similar devices.

An object of the invention is to provide a ventilator which is simple in construction and efficient in operation. One of the more 15 specific objects is to provide a ventilator for water closets, which may be readily operated at the will of a person utilizing the closet. Another specific object is to provide a gas 20 ejector especially applicable to water closet ventilators, which is simple in construction, highly efficient in operation and which may be manufactured at minimum cost. Still another specific object is to provide various 25 improvements in the details of water closet ventilator construction, which if embodied in existing ventilator or deodorizing systems, will greatly increase the efficiency and simplify the construction thereof.

A clear conception of several embodiments 30 of the invention may be had by referring to the drawings accompanying and forming a part of this specification in which like reference characters designate the same or similar parts in the various views.

Figure 1, is a side elevation partly in 35 section, of a water closet having a foot operated ventilator applied thereto.

Fig. 2, is an enlarged central vertical section through a gas ejector showing the details of construction thereof.

Fig. 3, is a side elevation partly in section, of a water closet having an automatically seat operated ventilator applied thereto.

Fig. 4, is an enlarged central vertical section through an improved form of trap showing the details of construction thereof.

The ordinary type of water closet to 50 which the invention may be applied, comprises essentially a water closet bowl 2, a flush tank 3 connected with the bowl 2 by means of a flush pipe 4, a water supply pipe 6 communicating with the interior of the flush tank 3, a vent pipe 5 communicating 55 with the sewer and with the external atmos-

sphere, and a main discharge pipe 7 connecting the bowl 2 with the vent pipe 5. The bowl 2 is usually provided with a hinged seat 15 and a cover 14, swinging upon a pivot 32, and has a base portion which rests directly upon the floor 43 of the toilet. The flush tank 3 is provided with the usual float controlled inlet valve, overflow pipe and flushing mechanism, not shown.

Referring specifically to Fig. 1, the foot 60 operated ventilator comprises essentially a gas ejector 1, a conduit or pipe 9 connecting the ejector 1 with the interior of the bowl 2, a water supply pipe 11 communicating with the main water supply 6 through a valve 20 and a branch pipe 10, and a gas discharge pipe 12 communicating with the vent pipe 5 through the trap 8 and pipe 13. The gas ejector 1 and trap 8 are preferably located within a suitable casing 16 provided 65 with a cover 17 for permitting ready access to these elements. The controlling valve 20 is located below and in front of the bowl 2, and is readily operable by the foot of a person utilizing the bowl 2, to open the valve, 70 by means of a treadle 18 which projects slightly above the floor 43. The valve 20 is normally maintained in closed position by means of a helical compression spring 19.

Referring specifically to Fig. 3, the ventilator which in this disclosure is automatically seat operated, comprises essentially a gas ejector 1, a conduit or pipe 9 connecting the ejector 1 with the interior of the closet bowl 2, a water supply pipe 11 connected 75 with the main water supply 6 through a valve 35 and branch pipe 10, and a gas discharge pipe 12 communicating with the vent pipe 5 through a trap 8 and pipe 13. The valve 35 is normally closed by means of a 80 helical compression spring 33 engaging a collar 34 carried by the valve stem 36. A lever 30 is mounted intermediate its ends upon the pivot 32, one end of the lever being adapted for engagement with the underside 85 of the collar 34, and the other end of the lever being formed as a finger 31 adapted for engagement with the lower surface of the seat 15. The spring 33 besides normally retaining the valve 35 in closed position, also 90 normally retains the seat 15 and cover 14 in the position disclosed in the figure. The gas ejector, 1, trap 8 and valve 35 are preferably located within a suitable casing 16 provided 95 with a cover 17 for permitting ready 100

110

access to these elements. The cover 17 at the point of penetration of the lever 30 therethrough, is provided with an elongated slot for permitting vertical movement of 5 the lever 30 to actuate the valve 35.

Referring specifically to Fig. 2, the gas 10 ejector comprises essentially a standard T fitting 21 the side branch of which is connected directly with the gas conduit or pipe 9. An element 22 having a passage 23 therethrough, is mounted within the T fitting 21, in such a manner that an annular chamber 25 surrounding the element 22 is formed. The through passage 23 has a local 15 constriction 24 and is provided with one or more openings 26 connecting the chamber 25 with the passage 23. The openings 26 are located beyond the constriction 24 and remote from the water supply pipe 11 which 20 communicates with the upper end of the element 22. The lower end of the element 22 is connected directly to the gas discharge pipe 12. The element 22 is provided with an abutment or clamping surface 27 which 25 is clamped against a washer 29 at one end of the T fitting 21 by means of a clamping nut 28 engaging screw threads at the upper end of the element 22. The nut 28 preferably engages a washer 29 which engages the 30 upper end of the T fitting 21, the washers 29 preferably being formed of aluminum or other relatively soft metal.

Referring specifically to Fig. 4, the trap 35 comprises essentially a casing forming a 35 chamber, a downwardly extending conduit 39 projecting into and terminating in the lower portion of the chamber, and an upwardly extending conduit 40 projecting into and terminating in the upper portion of 40 the chamber. The conduit 39 is formed in the upper trap element 37 and is connected directly with the ejector discharge pipe 12 by means of a coupling 41, while the conduit 40 is formed in the lower trap element 38 45 and is connected directly with the branch pipe 13 by means of a coupling 41. The elements 37, 38 are exactly alike in structure and differ only in their location. These elements may be joined by any suitable 50 means such as bolts. The interior of the trap is partly filled with water, the depth of which is determined by the upper extremity of the conduit 40, and which forms a liquid seal for the lower extremity of the 55 conduit 39.

The operation of the foot actuated device disclosed in Fig. 1 is as follows: The valve 20 is normally in closed position, the treadle 18 being in its uppermost position projecting slightly above the floor 43, and the ventilator being ineffective. If it is desired 60 to operate the ventilator, it is necessary only to place the foot upon the treadle 18 thereby opening the valve 20 and permitting water 65 to pass from the pipe 10 through the valve

20 and pipe 11 to the ejector 1. The water entering the ejector 1 flows through the passage 23 of the element 22 and has its pressure converted into velocity by virtue of the constriction 24 in the passage 23. The 70 water flowing at high velocity creates a negative pressure in the passage 23 beyond the constriction 24 and induces a flow of gas from the interior of the water closet bowl 2 through the conduit or pipe 9, chamber 75 25 and openings 26. The gas thus drawn into the lower extremity of the passage 23 mixes with the water and is carried into the trap 8 through the pipe 12 and conduit 39. The mixture of water and gas is discharged 80 into the pipe 13 through the conduit 40 and is eventually delivered into the vent pipe 5 where some of the gases are liberated from the mixture and flow to the external atmosphere while the remaining mixture flows 85 to the sewer. This eduction of gases continues as long as the valve 20 is maintained open, or until the foot is removed from the treadle 18. Upon closing the valve 20, the 90 flow of water through the ejector 1 ceases and causes the flow of gas from the bowl 2 to cease. The water last passing through the ejector 1 accumulates in the trap 8 as indicated in Fig. 4, and forms a seal for the 95 lower end of the conduit 39 preventing gases from flowing from the pipe 13 into the pipe 12.

The operation of the automatically seat operated ventilator disclosed in Fig. 3, is essentially the same as that of the foot operated device, except that operation is effected by pressing down the seat 15. Downward movement of the seat 15 moves the finger 31 down and swings the lever 30 above the pivot 32. This swinging of the lever 105 30 moves the collar 34 and stem 36 upwardly against the action of the spring 33 and opens the valve 35. Opening of the valve 35 permits water to flow through the passage 23 and causes an induced flow of gas from the 110 bowl 2, as above described. Operation of the ventilator ceases upon release of the seat 15 upon happening of which event the spring 33 and the water pressure acting upon the valve 35, automatically close the valve 115 35 and restore the lever 30 and seat 15 to the position disclosed in Fig. 3. The seat operated type of ventilator is objectionable due to the fact that the device is operating 120 all the while that a person is occupying the seat, although such operation may be desirable in public toilets where a manually operated device would not be utilized by persons unfamiliar with its actuation. The foot operated type would probably be more 125 desirable in private residences as it economizes in the use of water when operation of the ventilator is not necessary, and may be readily actuated at will without necessary occupation of the seat.

The ejector 1 may be manufactured at minimum cost as a standard T fitting 21 may be utilized to form the casing and the element 22 requires but a small amount of 5 machining. By forming the openings 26 through the element 22 at a point beyond the constriction 24 and remote from the water inlet, an ejector of maximum efficiency is produced. The efficiency of this ejector 10 is not dependent upon the nature of the operation of the ventilator, the device maintaining its high efficiency regardless of whether the operation is manually or automatically effected.

15 The trap 8 disclosed in detail in Fig. 4 is simple in construction and when used in connection with an ejector 1, augments the efficiency of such ejector since it produces minimum obstruction to the flow of the mixture delivered from the ejector. The trap 20 forms an efficient seal for preventing back flow of gases. A single pattern may be utilized to cast the elements 37, 38 and as these elements are interchangeable, only one 25 form need be carried in stock.

While the conduit 9 has been disclosed as communicating with the bowl 2 through the flush pipe 4, this conduit 9 may communicate directly with the bowl 2. The ventilators 30 may be applied to any existing water closet systems and need not be placed in a casing 16, although such concealment would be desirable in new installations. The cover 17 permits ready access to the various elements for 35 inspection and repairs.

It should be understood that it is not desired to be limited to the exact details of construction herein shown and described for obvious modifications may occur to a person 40 skilled in the art.

It is claimed and desired to secure by Letters Patent:—

1. In combination, a water closet bowl, conduit means having a constriction formed by gradually converging and diverging communicating portions, a water supply communicating with said gradually converging conduit portion, and gas conduit means connecting said bowl with said gradually diverging conduit portion beyond said constriction. 45 50

2. In combination, a water closet bowl, conduit means having a constriction formed by gradually converging and diverging communicating portions, a water supply communicating with said gradually converging conduit portion, and means forming a gas conduit connecting said bowl with said gradually diverging conduit portion beyond said constriction, said gas conduit being directed 55 inwardly toward said diverging portion and in the direction of flow of water therethrough.

3. In combination, a water closet bowl, conduit means having a local constriction 65 formed by gradually converging and diverging communicating portions, a controllable water supply communicating with the larger end of said gradually converging conduit portion, and means forming a gas conduit 70 connecting said bowl with said gradually diverging conduit portion beyond said constriction, said gas conduit being directed inwardly toward said diverging portion and in the direction of flow of water there- 75 through.

In testimony whereof the signature of the inventor is affixed hereto.

ARNOLD PFAU.
